FEED WATER HEATER FOR LOCOMOTIVES

Application filed November 6, 1929. Serial No. 405,225.

This invention relates to a feed water heater for locomotives and it has for some of its objects to provide a novel feed water heater which is so constructed that its installation cost is low; to provide a novel feed water heater that is so constructed that it has facilities for storage of heated water that may be fed into the locomotive boiler as needed; to provide a novel feed water heater having means to insulate the heated feed water from the unheated water in the main tank of the tender; to provide a feed water heater which has provision for pre-heating the water before it is delivered to the feed-water heating chamber; to provide a feed water heater which is so constructed that the feed water may be heated either by the steam exhausted by the cylinders of the locomotive or the exhaust from any one of the auxiliary devices, such as the headlight generator, air pump, feed pump, etc., or by a combination of exhaust steam from two or more of these sources, and to generally improve feed water heaters in various respects which will be more fully hereinafter set forth.

One advantage derived from our invention is that it is possible to heat the feed water while the engine throttle is closed, providing that at such times one or more auxiliary devices, such for instance as a headlight generator, air pump or feed pump is operating and thus furnishing exhaust steam that may be used for water-heating purposes.

A locomotive tender embodying our invention will be provided with one or more water-heating compartments in addition to the main water compartment, suitable means in the nature of insulation being provided between said compartments to prevent transference of heat from the water-heating compartment to the main compartment. This insulation may be provided for by separating adjacent compartments by means of a heat-insulating partition and in the preferred embodiment of our invention we propose to employ a plurality of such partitions thereby providing a passage compart-

ment that is located intermediate the water-heating compartment and the main water compartment and through which water is fed from the latter to the former. The various compartments have communication with each other through valved ports in the partitions which permit gravitational flow of water from the main water compartment into the water-heating compartment through the intermediate compartments but which prevent counterflow. This construction prevents the flow of heated water from the feed-water heating compartment back into the main compartment, thereby preventing preheating of the water in said main compartment with possible interference with the operation of apparatus which is dependent for its correct functioning upon a supply of cool water.

The heating of the water is done by the open heater principle, that is by delivering exhaust steam directly into the water contained in the water-heating compartment. Another feature of our invention relates to a novel construction by which any surplus steam that is not condensed in the water-heating compartment may be subsequently condensed and returned to the water-heating compartment instead of being discharged into the atmosphere and in connection with this feature we have provided means whereby the water of condensation from such surplus steam may be used for preheating the water before it is delivered to the water-heating compartment.

Further objects of the invention are to improve generally feed water heaters for locomotives in various ways hereinafter set forth.

In order to give an understanding of the invention we have illustrated in the drawings a selected embodiment thereof which, although not limiting the design, will now be described, after which the novel features will be pointed out in the appended claims.

Fig. 1 is a fragmentary view of a locomotive showing the tender portion thereof equipped with our improvements; the tender being shown in section;

Fig. 2 is a top plan view of the condenser for condensing the surplus steam;

Fig. 3 is a section on substantially the line 3—3, Fig. 1;

Fig. 4 is a top plan view of the front end of the tender;

Fig. 5 is a section on substantially the line 5—5, Fig. 1.

In the drawings, 1 indicates a locomotive 10 of which 2 is the tender. This tender is provided with the usual water compartment 3, the latter being shown as having the outlet opening 4 communicating with the pipe 5 which leads to the usual injector with which 15 locomotives are generally provided.

The outlet opening 4 is so located that the injector receives cold water from the main compartment 3 and thus it can always be used to feed water to the boiler in case of 20 a break down of the means employed for feeding to the boiler the water heated by the feed water heater, as required by the rules of the Interstate Commerce Commission.

In accordance with our invention we pro- 25 vide the tender with a water-heating compartment 6 which in this case is situated in front of the main compartment and beneath the shoveling plate 7.

A construction is provided which affords 30 heat insulation between the water-heating compartment 6 and the main water compartment 3 so as to reduce heat loss. This insulation feature may be provided for in various ways without departing from the in- 35 vention. In the construction herein shown, a passage compartment 8 is provided between the water-heating compartment 6 and the main water compartment 3, the construction being such that in passing from the 40 main compartment 3 to the water-heating compartment 6 the water has to pass through the passage compartment. This passage compartment is formed between two partitions 9 and 10 that extend, in this case, 45 transversely across the tender between the shoveling plate 7 and the bottom plate 11. These partitions are shown as heat insulated, each partition comprising a metal plate 12 combined with a layer 13 of suitable in- 50 sulating material.

Each partition has a port therethrough which is controlled by a check, or flap valve, the flap valves being indicated at 14 and 15 respectively. The flap valve 14 opens in- 55 wardly into the passage compartment 8 and the flap valve 15 opens inwardly into the heating compartment 6. These valves are preferably situated at opposite ends of the passage compartment 8, as shown in Fig. 3, 60 so that in flowing from the main water compartment 3 to the heating compartment 6, the water flows through the check valve 14 and then flows the length of the passage compartment 8 and then through the check valve 65 15.

The use of the partitions of insulating ma- 70 terial serves to reduce very materially any transfer of heat from the hot water in the compartment 6 to the water in the passage compartment 8, or that in the main compartment 3.

While we have herein illustrated the insulation feature of our invention as being associated with the use of a passage compartment 8, yet so far as the effect of the insulation is concerned this might be em- 75 ployed in a construction in which the water was admitted from the main chamber 3 directly into the water-heating compartment 6. The use of the passage compartment 8, however, has the advantage that it provides means for preheating the water taken from the main chamber 3 before it is delivered to the water-heating compartment 6 as will be hereinafter more fully set forth. 80

The heating compartment 6 has a dis- 85 charge port 16 with which communicates a pipe 17 leading to the feed device (not shown) by which the hot water is delivered to the boiler.

The water in the compartment 6 may be heated either by steam exhausted from the engine cylinders or by steam exhausted from the auxiliary devices such as a headlight generator, air pump, feed pump, etc. or by 90 both.

The water in the water-heating compartment 6 is heated on the open heater principle, that is, by delivering the exhaust steam directly into the water. This may be ac- 100 complished by any heat exchanger device suitable for the purpose. One convenient form of heat exchanger is in the form of one or more spray pipes which may conveniently have perforations throughout their length 105 so that the steam which is delivered to the spray pipes will be discharged into the water through the jet openings. In the illustrated embodiment of the invention there are two such spray pipes 18 and 19, each of which is perforated throughout its length and means are provided for delivering to the spray pipes the exhaust steam from the cylinders of the locomotive, or from any one or more 110 of the auxiliary devices. 115

As shown in the drawings, the pipe 18 is connected to receive exhaust steam from the locomotive cylinders and the pipe 19 is connected to receive exhaust steam from the auxiliary devices, but the steam from both 120 the cylinders and the auxiliary devices may be delivered to the same pipe or pipes.

With the construction illustrated, the ex- 125 haust steam from the engine cylinders, which may be taken therefrom in any usual way, is delivered from a pipe 20 to one leg of an inverted U-connection 21, the other leg of which is connected to the pipe 18. The upper end 22, or bridge of the U-con- 130 nection, is situated above the maximum

water level in the main water tank and is provided with a vacuum breaker 26, the purpose of which is to prevent the formation in the pipe 20 of a sub-atmospheric pressure when the locomotive is drifting or by reason of condensation of steam in said pipe, which sub-atmospheric pressure, if existent, would tend to draw water from the feed-water heating compartment into the engine cylinders. The exhaust from the auxiliary devices is connected to a pipe 23 which in turn connects to one leg of another inverted U-connection 24, the other leg thereof connecting to the pipe 19. The bend or bridge 25 of the U-connection 24 is also located above the maximum water level in the water compartment 3. The bridge or bend 25 is also provided with a vacuum breaker 26 which operates in the same manner as the vacuum breaker on the bridge or bend 22.

The water-heating compartment 6 is provided with a chamber or extension 27 which, in the illustrated embodiment of the invention, is located at one side of the tender and which communicates with the compartment 6. The U-connections 21 and 24 are shown as extending through this extension 27.

At the upper end, the extension 27 is shaped to form a steam dome 29 which is located at a higher level than the maximum water level of the tank 3 and this steam dome is provided with a hot water return 30 which may lead either to the main water compartment 3 or the passage compartment 8. In the illustrated embodiment of the invention the hot water return leads to the passage compartment 8. The dome is also provided with baffles 51 which have for their purpose to assist in separating any entrained water and/or air from the steam collecting in the steam dome as will be presently described. The hot water which is separated from the steam by the baffles 51 and which is returned to the passage compartment 8 through the hot water return 30 serves to heat the water in the passage compartment thereby preheating the water which is to be delivered to the water-heating compartment.

The pipes 20 and 23 may be provided with oil separators 31, and with valves 32 by which the passage of steam therethrough may be controlled. These pipes are also preferably equipped with check valves 40 to prevent any forward flow of water from the tender through the pipes 20, 23.

When the throttle valve is open and the locomotive is working, exhaust steam from the cylinders will be admitted to the water-heating compartment 6 through the spray pipe 18 thus heating the water therein and as the hot water is withdrawn from this compartment and fed into the boiler, water

from the main compartment 3 will flow into the heating compartment through the passage compartment 8. The flap valves, 14 and 15 prevent any back flow of hot water due to lurching of the tender, or surging 70 of water.

Any steam which is not condensed in the compartment 6 will, of course, rise through the chamber 27 and accumulate in the steam dome 29. There will naturally be more or less water brought up with the steam and this entrained water will be separated from the steam by baffles 51 and will flow back into the compartment 8 through the return 30 thereby acting to preheat the water in 75 the passage compartment before it is delivered to the water-heating compartment.

Our invention also comprehends a condenser device for condensing any steam or vapor which may be discharged from the steam dome 29. For this purpose we have shown a series of condenser pipes 33 situated in some convenient place, such as at the rear of the tender, said pipes being connected at one end to an intake header 34 80 and at the other end to a discharge header 35.

The intake header 34 is connected by a pipe 36 to the top of the steam dome and any steam which accumulates in the dome 95 29 will, therefore, flow through the pipe 36 into the condenser 33 where it will be condensed, the water of condensation flowing into the discharge header 35. This header 35 is shown as having a discharge or return pipe 37 connected thereto through which the water of condensation and any uncondensed steam may be taken to any desired point. In the illustrated embodiment of the invention this pipe 37 leads to the 100 passage compartment 8 although the destination of this pipe is not essential. Where the return pipe 37 leads to the passage compartment the hot water of condensation will serve to still further preheat the water in 105 the passage compartment before it is delivered to the water-heating compartment. The passage compartment thus provides means for preheating the water taken from the main compartment and before it is delivered to the water-heating compartment 110 and may be considered as a preheating compartment.

The discharge header 35 may, if desired, also be provided with an air vent pipe 39 120 through which air released from the water may escape to the atmosphere. Under normal conditions most of the steam passing over from the steam dome 29 will be condensed in the condenser and will be returned. 125

The chamber 27 extends to a point above the maximum water level in the main compartment 3 and the horizontal cross-sectional area of said chamber and the area of the dome 29 are of sufficient dimension so that 130

any entrained air and/or steam can be readily separated from the water in the chamber 27, the separation of the entrained water from the steam which is carried into the 5 steam dome being assisted by the baffles 51, and the separated water being delivered back through the return pipe 30. The liberated air passes over through the condenser and out through the vent 39. It is highly 10 advantageous to separate the entrained air from the water and steam, since the presence of air in water which is fed to the boiler will tend to increase pitting and corrosion of the boiler.

15 When the locomotive throttle is open the water in compartment 6 may be heated by steam delivered from the locomotive cylinders through pipe 18. When the locomotive throttle is closed, however, and any of 20 the auxiliary devices are operating, the exhaust steam from said devices may be used for heating water in compartment 6 or for increasing the temperature thereof, so that a considerable supply of water at a high 25 temperature is available for boiler feeding at practically all times. With this invention, therefore, the water in compartment 6 may be kept at a high temperature, whether or not the locomotive is actually working 30 steam.

52, 53 indicate baffles placed in the main compartment and in the passage compartment outside of the flap valves. The purpose of these baffles is to prevent these valves 35 from becoming opened by the surging of water in the compartments.

While we have illustrated herein a selected embodiment of our invention, we do not wish to be limited to the constructional 40 features shown.

We claim:

1. In a feed water heater for locomotives, the combination with a locomotive tender having a main water compartment, a feed- 45 water heating compartment and a combined passage and preheating compartment interposed between the water compartment and feed-water heating compartment and communicating with both, said compartment being arranged to permit gravitational flow from the water compartment to the feed- 50 water heating compartment through the passage compartment, non-return valves controlling said communications which permit such flow but prevent counter flow said feed- 55 water heating compartment having an upwardly-directed extension provided with a steam dome above the maximum water level 60 in the main compartment, of means to deliver exhaust steam into the feed-water heating compartment to heat the water therein, and a hot water return for delivering any 65 water carried into or steam condensed in the steam dome back to the passage and pre-

heating compartment thereby to preheat the water in said compartment.

2. In a feed water heater for locomotives, the combination with a locomotive tender having a main water compartment, a feed- 70 water heating compartment, there being a valved communication between said compartments, of a heat exchanger in the heating compartment, a steam pipe taking exhaust steam from the locomotive cylinders 75 and delivering said exhaust steam to the heat exchanger, said pipe having an inverted U-shape with the bend of the U located above the maximum water level in the main water compartment, and a vacuum breaker carried 80 by said steam pipe at the bend thereof, said vacuum breaker operating to prevent the formation in said pipe of a sub-atmospheric pressure due to the locomotive drifting or to condensation in said pipe thereby preventing water from the water-heating compartment being drawn into the locomotive cylinders. 85

3. In a feed water heater for locomotives, the combination with a locomotive tender 90 having a main water compartment, a feed-water heating compartment and a passage compartment between the first-named compartments, of a port between one end of the passage compartment and the main water 95 compartment, another port between the other end of the passage compartment and the water-heating compartment, whereby the water flowing from the main compartment to the water-heating compartment has to pass from one end to the other of the passage compartment, non-return valves controlling said ports, means for heating the water in the feed-water heating compartment, said feed-water heating compartment 100 having an outlet port located as far as possible from the point at which water is delivered to said heating compartment from the passage compartment, and means to heat 105 the water in the passage compartment. 110

4. In a feed-water heater for locomotives, the combination with a locomotive tender having a main water compartment and a feed-water heating compartment communicating therewith, of a flap valve controlling 115 said communication and permitting flow from the water compartment to the feed-water heating compartment but preventing counter flow, a heat exchanger in the feed-water heating compartment, means to deliver exhaust steam to said heat exchanger thereby to heat the water in said heating compartment, and a baffle in the main compartment on the inlet side of the flap valve 120 so constructed and arranged as to prevent said valve from being opened by surging 125 of water in the main compartment.

5. In a feed-water heater for locomotives, the combination with a locomotive tender having a water compartment, a feed-water 130

- heating compartment and a combined passage and preheating compartment interposed between the water compartment and feed-water heating compartment and communicating with both, of check valves between the water compartment and the combined passage and water-heating compartment and also between said latter compartment and the feed-water heating compartment which permit flow from the water compartment through the combined passage and preheating compartment to the feed-water heating compartment but prevent counter flow, means to heat the water in the feed-water heating compartment, and means to preheat the water in the combined passage and preheating compartment.
6. In a feed-water heater for locomotives, the combination with a locomotive tender having a water compartment, a feed-water heating compartment and a plurality of ported partitions separating said compartments and forming between them an intermediate compartment which communicates with both the water compartment and the feed-water heating compartment, of automatically-operating valves in the ports in said partitions to permit water to flow from the main compartment to the feed-water heating compartment through the intermediate compartment, but to prevent counter flow, means to heat the water in the feed-water heating compartment, and means to preheat the water in the intermediate compartment.
7. In a feed-water heater for locomotives, the combination with a locomotive tender having a water compartment, a feed-water heating compartment, and an intermediate compartment interposed between the water compartment and the feed-water heating compartment, there being valved communications between the intermediate compartment and each of the other compartments, of means to deliver exhaust steam directly to the water in the feed-water heating compartment thereby to heat the same, and means to utilize the heat in the steam which is not condensed in the feed-water heating compartment for preheating the water in the intermediate compartment.
8. In a feed-water heater for locomotives, the combination with a locomotive tender having a water compartment, a feed-water heating compartment and an intermediate compartment communicating with both the first-named compartments, of means to deliver exhaust steam into the feed-water heating compartment for heating the water therein, said compartment having an upward extension provided with a steam dome above the maximum water level therein in which steam not condensed in the water may accumulate and means to return to the intermediate compartment water of condensation formed from said accumulated steam thereby to preheat the water in said intermediate compartment.
9. In a feed-water heater for locomotives, the combination with a locomotive tender having a water compartment, a feed-water heating compartment and an intermediate compartment between the first-named compartments, there being a communication between said compartments arranged to provide for gravitational flow from the water compartment to the feed-water heating compartment through the intermediate compartment, said feed-water heating compartment having an upward extension provided with a steam dome, means to deliver exhaust steam into the feed-water heating compartment for heating the water therein, means for separating entrained water from the steam in the steam dome, and means for returning said entrained water from the steam dome to the intermediate compartment, whereby the water in said intermediate compartment is preheated.
10. In a feed-water heater for locomotives, the combination with a locomotive tender having a water compartment, a feed-water heating compartment and an intermediate compartment, there being a communication between said compartments arranged to provide for gravitational flow from the water compartment to the water-heating compartment through the intermediate compartment, said feed-water heating compartment having an upward extension provided with a steam dome, means to deliver exhaust steam into the feed-water heating compartment for heating the water therein, means for separating entrained water from the steam in the steam dome, and means for returning to the intermediate compartment both the separated entrained water and water of condensation derived from the excess steam delivered to the water-heating compartment, whereby the water in said intermediate compartment is preheated.
11. In a feed-water heater for locomotives, the combination with a locomotive tender having a water compartment, a feed-water heating compartment and a passage compartment interposed between the water compartment and the feed-water heating compartment, said passage compartment extending transversely of the direction of movement of said tender, of means to heat the water in the feed-water heating compartment, two check valves, one between the water compartment and the passage compartment and the other between said passage compartment and the feed-water heating compartment, said valves having a staggered arrangement and permitting flow from the water compartment through the passage compartment to the feed-water heating compartment but preventing counter flow.

terflow due to surging of the water in said compartments caused by movement of the locomotive.

12. The combination with a locomotive tender having a water compartment, a feed-water heating compartment and a plurality of ported partitions extending transversely to the direction of movement of the tender and separating said compartments and forming between them a passage compartment, of means to heat the water in the feed-water heating compartment, the ports in said partitions delivering water in the same direction and the port in one partition being situated adjacent one end of the passage compartment and that in the other partition adjacent the other end of said compartment, and automatically-operating valves controlling said ports and permitting water to flow from the main compartment to the heating compartment through the passage compartment but preventing counterflow due to surging of the water caused by movement of the locomotive.
13. In a feed-water heater for locomotives, the combination with a locomotive tender having a water compartment, a feed-water heating compartment and an intermediate compartment communicating with both the first-named compartments, of means to deliver exhaust steam into the feed-water heating compartment for heating the water therein, said feed-water heating compartment having an upward extension provided with a steam dome above the maximum water level therein in which steam not condensed in the water-heating compartment may accumulate, means to return to the intermediate compartment water of condensation formed from any excess steam delivered to the feed-water heating compartment thereby to preheat the water in said intermediate compartment, and a return duct connecting the steam dome to one of the compartments to permit return to said compartment of water that is separated from the steam in said upward extension.

14. In a feed-water heater for locomotives, the combination with a locomotive tender having a water compartment and a feed-water heating compartment, there being a valved communication between said compartments, means to heat water in the feed-water heating compartment, the latter having an outlet through which the hot water is delivered to a feeding device designed for feeding hot water to the locomotive boiler, a pipe communicating with the main water compartment and leading to a feed device which will feed cold water to the boiler but which is inoperative to feed hot water, and means for preventing transference of heat in appreciable amounts from the hot water in the feed-water heating compartment to the cold water in the water com-

partment, whereby the water in the water compartment will be maintained at a temperature suitable for the operation of the boiler feed device which takes water directly therefrom.

15. In a feed-water heater for locomotives, the combination with a tender having a main water compartment and a feed-water heating compartment, said feed-water heating compartment having an upwardly-directed extension, there being a valved communication between said compartments with the inlet into the feed-water heating compartment below said upwardly-directed extension, said feed-water heating compartment being situated relative to the main water compartment so that there is a gravitational flow of water from the main compartment to the feed-water heating compartment, means for delivering exhaust steam into the feed-water heating compartment for heating the water therein, a connection for the withdrawal of water from said feed-water heating compartment, the upwardly-directed extension of the feed-water heating compartment having a generous cross-sectional size in a horizontal direction, whereby any steam and/or air contained in the water in the feed-water heating compartment may rise through the water into the upper portion of the extension without causing an upward flow of water in said extension.

16. In a feed-water heater for locomotives, the combination with a locomotive tender having a plurality of compartments, one of which is a main water compartment, another of which is a feed-water heating compartment and the remainder of which constitute a passage through which water flows from the main compartment to the feed-water heating compartment, of means to deliver exhaust steam into the feed-water heating compartment for heating the water therein, said compartment having an upward extension provided with a steam dome above the maximum water level therein in which steam not condensed in the water may accumulate, and means to return the water of condensation formed from said accumulated steam into a compartment between the main water compartment and the feed-water heating compartment.

17. In a feed-water heater for locomotives, the combination with a locomotive tender having a plurality of ported partitions extending in the same direction and dividing the water space of the tender into a plurality of compartments, one of which is a main water compartment, another of which is a feed-water heating compartment, and the remainder of which provide a passage communicating with both the main water compartment and the feed-water heating compartment, said compartments being arranged for gravitational flow of water from

the main water compartment through said passage to the feed-water heating compartment, of non-return valves controlling the ports in said partitions, and means to heat 5 the water in the feed-water heating compartment, the ports leading into said passage from the main water compartment and from said passage into the feed-water heating compartment being on opposite sides of said 10 passage and delivering water in the same direction, one of said ports being adjacent one end of the passage and the other port being adjacent the other end of said passage, whereby said passage functions to dissipate any surge of water through the port 15 leading from the main water compartment.

In testimony whereof, we have signed our names to this specification.

CERTIFICATE OF CORRECTION.

Patent No. 1,900,697.

March 7, 1933.

MYRON W. DOLE, ET AL.

It is hereby certified that error appears in the printed specification of the above numbered patent requiring correction as follows: Page 5, line 7, claim 5, for "an" read "and"; line 52, claim 8 for the misspelled word "locomitives" read "locomotives", and line 54, same claim, after "feed-water" insert the word "heat ing"; and that the said Letters Patent should be read with these corrections there- in that the same may conform to the record of the case in the Patent Office.

Signed and sealed this 25th day of April, A. D. 1933.

(Seal)

M. J. Moore,
Acting Commissioner of Patents.
